FLASHING SIGNAL LIGHT UNIT

Robert D. Kahn, Rockville Centre, N.Y., assignor to
Fedtro, Inc., Rockville Centre, N.Y., a corporation
of New York

Filed Apr. 8, 1968, Ser. No. 11,355

Term of patent 14 years

U.S. Cl. D72—1
Int. Cl. D29—99

FIG. 1

FIG. 2

FIG. 4

FIG. 3

FIG. 5

FIG. 1 is a three-quartered perspective view of the flashing signal light unit showing the front of the unit; FIG. 2 is a top plan view of the unit;

FIG. 3 is a front elevational view of the unit, the rear view being a mirror image thereof.

FIG. 4 is a right side elevational view of the unit, the left side elevational view being a mirror image of the right side elevational view; and

FIG. 5 is an enlarged portion of the faceted surface shown in FIGS. 1 and 3 which is understood to be continuous over the entire face of the lens.

I claim:

The ornamental design for a flashing signal light unit, as shown and described.
